UNITED STATES PATENT OFFICE.

JAMES MOXON SCHOFIELD, OF STOCKTON, CALIFORNIA.

ODORLESS SEWER SYSTEM.

933,121.

Specification of Letters Patent. Patented Sept. 7, 1909.

Application filed September 8, 1908. Serial No. 451,949.

To all whom it may concern:

Be it known that I, JAMES M. SCHOFIELD, a citizen of the United States, residing at Stockton, in the county of San Joaquin, State of California, have invented certain new and useful Improvements in Odorless Sewer Systems; and I do declare the following to be a full, clear, and exact description of the same, such as will enable others skilled in the art to which it appertains to make and use the same, reference being had to the accompanying drawings, and to the characters of reference marked thereon, which form a part of this application.

This invention relates to sewer systems of all kinds either for city service or for private use such as for country residences, the object of the invention being to produce a system which will be perfectly odorless in all respects and one which will be out of sight and in no way interfere with the general appearance of a residence place and one which when used as a city service will not necessarily interfere with any farming operations that it might be desired to carry on over soil covering the sewer system. Also to produce a system in which the liquids will be disposed of readily and with no danger of overflow. Also to produce a simple, inexpensive and effective system for the purpose.

These objects I accomplish by means of vaults suitably submerged beneath the surface of the ground and having removable lids, the main sewer pipes discharging into said vaults, division walls in said vaults to maintain a strictly liquid receptacle on one side and the heavy deposits on the other. A plurality of submerged pipes are spaced apart around said vaults and communicate preferably with the first water carrying sand and gravel strata in the earth. A pipe leads from beneath the desired liquid level in said liquid receptacles to the first of said pipes and on a level with said liquid in said receptacle and all of the said pipes are connected by means of pipes disposed at the level of said pipe entering said first named pipe. Also such other and further construction and relative arrangement of parts are employed as will appear by a perusal of the following specification and claims.

In the drawing similar characters of reference indicate corresponding parts in the view.

The figure in the drawing represents a vertical section of my complete improved sewer system.

Referring now more particularly to the characters of reference on the drawings 1 designates the surface of the ground. Submerged below such surface is a vault or tank 2 built of brick, cement or other desired material and having a removable lid 3. A wall 4 extends across the tank 2 dividing the same into a large chamber 5 and a smaller chamber 6, there being a plurality of holes 7 in the wall 4 near its upper end and communicating from the chamber 5 to the chamber 6.

8 designates the main sewer discharge pipe which is provided with a trap 9 previous to its entry into the tank 2. The said pipe 8 runs at an incline into the vault and to a point below the permitted level of the liquid in said vault.

10 are a plurality of pipes or casings submerged beneath the surface of the earth and having removable lids 10, which pipes extend to the water sand and gravel strata as shown in the drawing. These pipes are all connected by means of pipes 11 disposed at the level of the desired level of the fluid in the tank 2, one of said pipes 10 being connected with said tank by means of a pipe 12 inclined into said tank to a point below the desired level of the liquid in the tank 2 but connecting with the pipe 10 at such level.

In practice the pipe 8 discharges the sewage into the tank 2 and the heavy deposits 13 settle to the bottom of the chamber 5 and the liquid fills such chamber and flows through the holes 7 into the chamber 6 and thence through pipe 12 and pipes 11 into the pipes 10 from whence it drains into the water carrying strata 14.

The object of the holes 7 being below the permitted liquid level is so that floating matter will not obstruct the same but will be on the top of the liquid leaving a clear communication through such holes. For a similar reason the pipe 12 is inclined into the liquid below its level to keep every matter other than liquid out of the pipes 10, as is necessary to the functions of said pipes.

The liquid is carried from the pipes 10 by means of the running water in the strata 14 and a plurality of such pipes are provided in order to prevent overflow of the system, since when the liquid in any one of said

2 pipes rises to the level of the liquid in said tank 2 it overflows into the next succeeding pipe 10 through the pipe 11.

When the chamber 5 fills with solid matter the lid 3 may be removed and such solid matter excavated from the chamber.

Should any of the pipes 10 become clogged from any reason the cap 10^a can be removed and such pipes cleansed.

10 For a city service a plurality of the tanks 2 could be provided, either connected or otherwise and so constructed that when one was being excavated the remaining ones would act independently thereof. The tanks 15 2 can be of any depth desired and the pipes 10 can communicate either with the first water strata or with deeper ones as may be desired.

10 The feature of the device which makes it entirely odorless is that the liquid is continuously carried out of the tank and pipes and thus does not rise above its certain predetermined level and thus does not force the odorless gases out of the tank but rather 25 absorbs and carries the same away by the means described.

From the foregoing description it may be readily seen that I have produced a sewer system which substantially fulfills the objects of the invention herein.

30 While this specification sets forth in detail the present and preferred construction of my improved sewer system, still in practice such deviations from such detail may be

resorted to as do not form a departure from 35 the spirit of the invention.

Having thus described my invention what I claim as new and useful and desire to secure by Letters Patent is:—

1. An odorless sewer system comprising a 40 tank submerged beneath the soil, a plurality of pipes disposed around said tank and opening into a natural subterranean water stratum in the soil, means connecting said pipes with said tank at a predetermined level, as 45 set forth.

2. An odorless sewer system comprising a tank submerged below the ground and having a removable cap, a discharge pipe running obliquely into said tank, a trap in 50 said discharge pipe, said discharge pipe discharging into said tank below a predetermined liquid level therein, a wall in said tank extending upward to such predetermined level, a plurality of holes in said 55 wall below said predetermined level, an outlet pipe extending outward from said tank below the said liquid level to a point in alignment with said level, and a plurality of vertical pipes connected with said outlet 60 pipe and with each other all at the same level, as described.

In testimony whereof I affix my signature in presence of two witnesses.

JAMES MOXON SCHOFIELD.
